United States Patent Office.

C. POTTER, JR., OF WESTERLY, RHODE ISLAND.

Letters Patent No. 73,196, dated January 7, 1868.

IMPROVEMENT IN FEED-GAUGES FOR PRINTING-PRESSES.

The Schedule referred to in these Letters Patent and making part of the same.

TO ALL WHOM IT MAY CONCERN:

Be it known that I, C. POTTER, Jr., of Westerly, in the county of Washington, and State of Rhode Island, have invented a new and improved Adjustable Feed-Guide for Printing-Presses; and I do hereby declare that the following is a full, clear, and exact description thereof, which will enable others skilled in the art to make and use the same, reference being had to the accompanying drawings, and to the letters of reference marked thereon.

This invention relates to a new and improved adjustable feed-guide for printing-presses, and has for its object the facilitating of the adjustment of the guide, one screw only being manipulated in order to admit of the guide being adjusted in two different directions, which are required. In the accompanying sheet of drawings—

Figure 1 represents a side sectional view of my invention, taken in the line *x x*, fig. 2.

Figure 2, a plan or top view of the same, with the old or present plan shown in red.

Figure 3, a side sectional view of the old or present plan, taken in the line *y y*, fig. 2.

Similar letters of reference indicate like parts.

A represents a shaft, on which the guides B are secured, and C represents a section of the drum-cylinder, which is provided, as usual, with nippers, to catch the sheets and convey them around to the form on the bed below; and D represents a portion of the feed-table, on which the sheets of paper are fed to the press. The guides B, it will be understood, serve as stops for the edges of the sheets to bear or rest against previous to the nippers on cylinder C grasping them. These guides insure the sheets being grasped while the latter are in a proper relative position with the cylinder, in order to admit of the sheets being correctly registered, or receiving the impression evenly, so as to leave a margin of uniform width at its sides and at the top and bottom. The guides are composed of a metal strip or plate, *a*, bent downward at its front end, as shown at *b*, fig. 1. The plate is secured by two screws, D D', to a box, composed of two parts, E E', which encircle or grasp the shaft A, and are made to clutch it firmly by means of the screws D D', which pass through an oblong slot, *c*, in the strip or plate *a*, through the upper part E, and into the lower part E' of the box, as shown clearly in fig. 1. The strip or plate *a* is held in position by the screw D', which is provided with a flat head, *d*, to serve as a thumb-piece for the convenience of turning it. By unscrewing the screw D', the box may be loosened on the shaft A, and consequently the box moved laterally on the shaft, and the guide *a* consequently moved or adjusted laterally; and while the screw D' is thus unscrewed, the guide *a* may be adjusted further forward or backward, as desired, as the screw D' not only clamps the two parts E E' to the shaft, but also clamps the strip or plate *a* to the upper part E. The screw D simply holds the front ends of the parts E E' of the box together, and also serves to retain the guide in proper place or position. My improvement, therefore, possesses the advantage of requiring but a single manipulation of one screw only to adjust the guide, either laterally, or forward and backward.

Having thus described my invention, I claim as new, and desire to secure by Letters Patent—

The two screws D D' and slotted guide-plate B, in combination with the box, composed of two parts, E E', fitted to the shaft A, and all arranged substantially in the manner as and for the purpose set forth.
